ABSTRACT OF THE DISCLOSURE

The invention relates to a snap lock for a container with a spring loaded lid hinged thereto. The snap lock comprises a concealed catch mechanism and a protruding grip. It locks itself when the lid is pressed against the container body and it is released by displacing the grip in either one of two opposite directions.

The invention relates to a container with a lid hinged thereto spring biased to move the lid from a closed position into an open position, and more particularly, to a container with a spring loaded lid which is held in its closed position by a snap lock.

Containers with a snap lock according to the invention are useful for very many purposes and may take a great variety of shapes. The invention is particularly advantageous for cigarette cases or jewel boxes.

There are already known containers with a spring loaded lid held in closed position by a snap lock. Such containers are disclosed, for instance, in Patent 3,165,225. This patent describes a container, the lid of which is slideable in both directions on the pintle of a hinge such as a piano hinge against spring pressure. The lock retains the lid only if the lid is centered in reference to the container. The lock is released by applying lateral pressure upon one of the narrow sides of the lid causing displacement thereof.

It is an object of the invention to provide a novel and improved snap lock for containers with a spring loaded lid hinged thereto, said snap lock having a grip which is externally accessible for actuation, and a locking mechanism which is concealed and so arranged that upon displacement of the grip in either one of two directions, the lid is released for opening by its spring loading.

The afore-pointed-out object, feature and advantage of the invention and other objects, features and advantages which will be pointed out hereinafter, are obtained by providing a snap lock having a slide slideable in opposite directions and mounting a catch pin. The catch pin coacts with a stationarily mounted receiver which is generally roof or wedge shaped on its side facing the catch pin and has on this side a crosswise recess. This recess is engageable with the catch pin when the latter is in a predetermined position in reference to the receiver. Springs disposed on both sides of the displaceable slide urge the same into the position in which the catch pin engages the recess, thereby locking the snap lock. The snap lock is released by forcing the slide against the action of the respective spring into a position in which the catch pin on the slide is out of engagement with the recess of the receiver.

The slide is preferably mounted on a frame which is secured to the rim of the container and is open on its downwardly facing side so that the frame can be fitted upon the container rim.

2

The slide is preferably mounted on the container rim and the receiver on the lid.

In the accompanying drawing, a preferred embodiment of the invention is shown by way of illustration and not by way of limitation.

In the drawing:

FIG. 1 is a perspective view of the upper part of a container with a lid hinged thereto, the lid being shown in its open position;

FIG. 2 is a perspective view similar to FIG. 1, but showing the lid in its closed position;

FIG. 3 is a fragmentary plan view on an enlarged scale, seen in the direction of the arrow III of FIG. 1;

FIG. 4 is a section taken on line IV—IV of FIG. 3;

FIG. 5 is a fragmentary view seen from the inside of the container in the direction of arrow V of FIG. 1;

FIG. 6 is a fragmentary view upon the front rim of the lid; and

FIG. 7 is a section taken on line VII—VII of FIG. 6.

Referring now to the figures more in detail, there is shown the upper part of a container 1 of substantially rectangular configuration with a lid 12 hinged thereto by a spring loaded hinge 11. This hinge is shown as a conventional piano hinge which biases the lid into its open position. The container has on its rim a frame 2 which is of generally U-shaped cross-section and is fastened to the walls of container 1 in a conventional fashion by inserting the rim of the container proper into the open side of the frame and securing the container rim in the frame.

The frame mounts a slide 15 which will be more fully described hereinafter, and lid 12 supports fixedly secured thereto a receiver 13 which also will be more fully described hereinafter.

As is clearly shown in FIG. 2, the lid when closed is flush with the frame of the container and the slide is centered in reference to the lid and the frame.

Referring now to the slide 15 shown in detail in FIGS. 3, 4 and 5, the slide comprises a guide portion 5 lengthwise slideable in frame 2. The portion is urged by springs 6 and 7 disposed on opposite sides of the guide portion into a predetermined position, preferably centered in reference to container 1 and its frame 2. Springs 6 and 7 abut about on one end against guide portion 5 and on the other end against abutment members such as U-shaped members 8 secured in frame 2. As is evident, guide portion 5 and the springs coacting therewith are concealed within the frame. The slide is fixedly secured or integral with a grip 3 mounting a catch pin 4. This catch pin has preferably a roof shaped or wedge shaped configuration as can best be seen in FIG. 5.

Receiver 13 which, as previously explained, is fixedly mounted to the lid and more specifically in a cut-out 12a thereof, comprises a receiver member 14 which preferably also has a generally roof shaped or wedge shaped cross-sectional outline, as can best be seen in FIG. 6. The apex edge 4a of catch pin 4, and the apex edge 14a of receiver member 14 are so disposed that they face each other. The apex edge of member 14 includes a crosswise recess 14b.

Assuming now that it is desired to close lid 12. To this end, the lid is pressed down by hand until receiver member 14 or more specifically its apex edge 14a engages catch pin 4. Theoretically, edge 14a may squarely engage apex edge 4a of pin 4, but more likely receiver member 14 will engage catch pin 4 somewhat to the left or right of the apex edge, and in any event the pin will be forced to slide along one side or the other against the action of spring 6 or spring 7 when the closing pressure on lid 12 is increased.

Assuming that catch pin 4 slides along one of the sides of receiver member 14, guide portion 5 will be pressed sidewise against the action of the respective spring 6 until finally recess 14b is in alignment with catch pin 4. The

compressed spring 6 will now snap the guide portion 5 toward its center position. As a result, catch pin 4 is retained in the recess of the receiver member. The lid is now locked to the container.

In this connection, it should be pointed out that catch pin 4 need not be triangular as shown, but may have any configuration such that the pressure of receiver member 14 against the catch pin when the lid is pressed toward its closing position causes displacement of guide portion 5 and thus movement of the catch pin into a position in which it can enter recess 14b. For instance, a round or oval pin would be suitable for the purpose.

To release the slide, grip 3 is selectively pressed toward the left or the right as seen in FIG. 3. The corresponding displacement of guide portion 5 against the action of the respective spring 6 or 7 will cause catch pin 4 to move out of receiver recess 14b, thereby releasing the snap lock for opening of the lid by hinge 11.

While the invention has been described in detail with respect to a certain new preferred example and embodiment of the invention, it will be understood by those skilled in the art, after understanding the invention, that various changes and modifications may be made without departing from the spirit and scope of the invention, and it is intended, therefore, to cover all such changes and modifications in the appended claims.

I claim:

1. A snap lock for a container with a hinged lid spring biased to swing the lid from a closed position to an open position, said snap lock comprising in combination:

- (a) a slide slidably mounted on a rim portion of the container outwardly protruding therefrom, said side being slidable parallel to the rim portion in either direction;
- (b) spring means acting upon opposite sides of said slide to bias the same into a predetermined midposition in reference to said rim portion;
- (c) a catch pin protruding from said slide;
- (d) a receiver for said catch pin fixedly secured to the lid of the container, said receiver having a generally tapered cross-section, the tapered edge of the receiver facing said catch pin in substantial alignment therewith when the slide is in its midposition and including a recess extending parallel to the displacement direction of the slide and the catch pin pro-

5
10

truding therefrom, pressing of the lid toward its closed position causing engagement of the pin with either slanted side of the receiver;

(e) whereby the slide is displaced out of the midposition and the pin is displaced into a position of alignment with said recess of the receiver, the action of the respective spring means moving the pin into engagement with the recess and the lid into the midposition thus locking the lid, displacement of the slide out of the midportion in either direction withdrawing the pin from the recess to release the pin for opening of the lid by the action of the spring bias of the lid.

2. A snap lock according to claim 1 wherein said receiver is in the form of a pin having a substantial triangular cross-sectional configuration, the apex edge of said pin including said recess crosswise thereto.

3. A snap lock according to claim 1 wherein said catch pin has a cross-sectional configuration defining an apex facing the tapered edge of the receiver.

4. A snap lock according to claim 3 wherein said catch pin has a substantially triangular cross-section, the apex edge of the pin being directed toward the edge of said receiver.

5. A snap lock according to claim 1 and comprising a 25 channeled frame attachable upon the rim portion of the container, and wherein said slide comprises a guide portion lengthwise slidable in said frame concealed by the same and a grip portion disposed juxtaposed to the outside of the side branch of the frame and joined to said 30 guide portion, said catch pin protruding from said grip portion and said spring means being disposed in said frame on opposite sides of said guide portion coating with the same to bias the guide portion and thus the catch pin into said predetermined midposition in reference to the receiver.
